[57] CLAIM

The ornamental design for a seat, as shown and described.

DESCRIPTION

FIG. 1 is a top plan view of the seat comprising my new design;

FIG. 2 is a side elevational view thereof;

FIG. 3 is the opposite side elevational view thereof;

FIG. 4 is a front elevational view thereof; and,

FIG. 5 is a back elevational view thereof.

The broken line showing of leg members is for illustrative purposes only and forms no part of the claimed design.
